UNITED STATES PATENT OFFICE.

SAMUEL CANADA MILLER, OF LOUISVILLE, KENTUCKY, ASSIGNOR TO MATTINGLY & MOORE DISTILLERY CO., OF LOUISVILLE, KENTUCKY, A CORPORATION OF KENTUCKY.

NONREFILLABLE BOTTLE.

Application filed June 12, 1924. Serial No. 719,616.

The present invention relates to improvements in non-refillable bottles and has for an object to provide a fitment of light inexpensive construction adapted to be manufactured separately from the bottle and applied thereto quickly and conveniently so as to avoid its subsequent removal or tampering with the enclosed operating parts.

Another object of the invention consists in certain modifications in the neck of the bottle to receive the fitment and a cup which encloses the fitment and is useful in dispensing the contents of the bottle.

With the foregoing and other objects in view, the invention will be more fully described hereinafter, and will be more particularly pointed out in the claim appended hereto.

In the drawings, wherein like symbols refer to like or corresponding parts throughout the several views.

Figure 1 is a fragmentary side view of the bottle with the improved fitment in place showing the cup in section.

Figure 2 is a similar view of the bottle with a part broken away and showing the fitment in section with the cup dotted in.

Figure 3 is a view similar to Figure 2 showing the inverted position of the parts with the cup removed.

Figure 4 is a fragmentary perspective view showing a part of the enclosing casing.

Figure 5 is a similar view of the attaching ring.

Figure 6 is a perspective view of the perforated gasket.

Figure 7 is a similar view of the valve, and

Figure 8 is also a perspective view of the valve restraining element.

Referring more particularly to the drawings 9 designates a bottle having a neck 10 of short length provided with the external threads 11 for engaging similar threads upon the inverted cup 12. This cup is of aluminum or other appropriate material and encloses the neck and the non-refillable fitment. The neck is provided with a reduced upper end having an annular groove 13 into which

is spun the lower portion of the ring 14 of the fitment casing. The casing is in two parts, the cylindrical main casing body 15 being provided with an outturned flange 16 along its lower edge for fitting within the inturned flange 17 upon the upper end

of the ring 14, the ring being of slightly greater diameter than the flange 16 and adapted to slide thereover in an axial direction. The casing body 15 is provided with a closed top 18 except for the open mouth 19 adapted to receive the cork or stopper 20.

Within the ring 14 is placed a gasket 21 of cork or other compressible material, the gasket being provided with a central opening 22 and the edge portion of the gasket being clamped between the upper end of the bottle neck and the flange 16 of the body. The opening 22 in the gasket 21 is of less diameter than the diameter of the casing body 15 and the rim or flange 23 of the inverted cup shaped valve 24 is adapted to surround the opening 22 and tightly engage the gasket about the opening to prevent the entrance of liquid poured in through the liquid out through the mouth 19.

The liquid, however, in the inverted position of the parts is permitted to flow out from the bottle without interference from the valve 24 by reason of the fact that the valve restraining member 25, which is a cup shaped substantial counter part of the valve is placed with its closed bottom edge against the closed top surface of the valve and spaced projections or legs 26 on the flange of the member 25 are adapted to strike beneath the closed top 18 of the fitment casing. Between the projections or legs 26 are spaces for the passage of the liquid out through the mouth 19.

The casing 15, ring 14, valve 24 and valve restraining member or stop 25 may be all made of thin metal and the valve 24 is preferably loose from the stop member 25 in order to prevent tampering with the valve through the mouth 19 with an implement whereby to hold the valve away from its seat. While the member 25 is accessible for this purpose the valve 24 is not and will drop to its seat when the bottle is turned upright in an attempt to pour in a spurious liquid.

In the use of the device, the fitment is not put in place until the bottles have been filled with the genuine contents at the authorized filling plant. The fitment is then put in place, suitable pressure being placed upon the gasket 21 in order to avoid leakage at this point and the rim 14 is spun into the groove 13 of the bottle neck. With this

construction it is a most difficult matter to remove the fitment but should it be removed, of course the fact of its removal will be an evidence to purchasers that a counterfeiting of the original has taken place and if any damage is done the fitment which will be apparent from any attempt to dislodge it this will act as a tell-tale warning the public of the unauthorized tampering and to 10 beware of the contents.

The cup 12 is screwed in place concealing the entire fitment and giving a neat and attractive appearance to the bottle when sold in commerce. The neck of the bottle is 15 short, the fitment compact and consequently the cup can be of adequate size without giving the bottle a top heavy appearance. When use of the contents is desired, the cup 12 is removed by unscrewing and the bottle 20 is inverted to pour the contents into the cup in the manner shown in Figure 3, whereupon the valve and valve member will drop by gravity away from the gasket 21 permitting the contents to pass through the opening 22 in the gasket and out about the spaces at the sides of the projection 26 of the valve stop member 25, passing out 25 through the mouth 19 and into the cup.

After the contents are removed it will be 30 impracticable to refill the bottle owing to the fact that in the upright position of the bottle necessary to its replenishment, the valve 24 will seat upon the gasket 21 as shown in Figure 2 and any attempt to pour 35 liquid into the bottle will merely act to more tightly close the valve.

It is obvious that various changes and

modifications may be made in the details of construction and design of the above specifically described embodiment of this invention without departing from the spirit thereof, such changes and modifications being restricted only by the scope of the following claim.

What is claimed is:—

In combination with a bottle having a neck with external threads at the base thereof and an annular groove outwardly of the external threads, of a flexible gasket having a restricted opening placed upon the 50 bottle neck, a casing having its lower end open and provided with an out-turned flange seated upon said gasket, said casing having an upper end with an opening therein, a stopper placed in said opening, a ring of a 55 diameter to extend about said bottle neck and gasket and having its lower portion interlocked in said groove of the neck, said ring having an upper inturned flange for sliding freely over said casing but interlocking with said flange of the casing, an inverted cup shaped valve having a continuous flange adapted to float in said casing and to rest upon the gasket about the restricted opening, a cup shaped restraining member also floating in the casing and independent of said valve and having upwardly projecting legs for engaging against the upper end of the casing, and a cup 60 entirely surrounding the neck, casing and ring 65 and having threads to engage the threads on the neck.

SAMUEL CANADA MILLER.
